(57) **CLAIM**

The ornamental design for a display screen with a football-themed keyboard graphical user interface, as shown and described.

DESCRIPTION

The FIGURE is a front view of a display screen with a football-themed keyboard graphical user interface showing the new design.

The outermost broken line illustrates a display screen or portion thereof and forms no part of the claimed design. The remaining broken lines illustrate portions of the graphical user interface that form no part of the claimed design.

1 Claim, 1 Drawing Sheet
